UNITED STATES PATENT OFFICE.

CHARLES W. HART, OF TROY, NEW YORK.

DESIGN FOR A HEAD FOR MOP-STICKS.

SPECIFICATION forming part of Design No. 34,538, dated May 21, 1901.

Application filed April 4, 1901. Serial No. 54,397. Term of patent 14 years.

To all whom it may concern:

Be it known that I, CHARLES W. HART, a citizen of the United States, residing at Troy, in the county of Rensselaer and State of New

5 York, have invented and produced a new and original Design for a Head for Mop-Sticks, of which the following is a specification, reference being had to the accompanying drawings, forming part thereof.

10 Figure 1 of the drawings is a bottom plan view of a head for mop-sticks, showing my new design. Fig. 2 is a side elevation of the same.

As shown in the drawings, the leading or

material feature of my design consists in the 15 hook-form terminals 1 1 at the ends of the T-arms 2 2, projecting oppositely from the hub 3 of the head.

What I claim as new, and desire to secure by Letters Patent, is—

20 The design for a head for mop-sticks herein shown and described.

In testimony whereof I have hereunto set my hand this 1st day of April, 1901.

CHARLES W. HART.
